HYDRAULIC PRESSURE-APPLYING DEVICE

Herbert E. Page, Pasadena, Calif.

Application March 6, 1944, Serial No. 525,259

3 Claims. (Cl. 100—71)

My invention relates to hydraulic pressure generating and applying devices. One of the aims of my invention is to provide a device which utilizes a plurality of work chambers and pistons of progressively increasing diameters and in which device there is an automatic selection and utilization of the piston to meet the pressure requirements of a given operation.

Another object is to provide a hydraulic device in which the work pistons project from opposite sides of the body in position to be utilized simultaneously to apply pulling pressure at one side of the body and a pushing or lifting pressure at the other side of the body.

Another object is to provide, in such a device, means for relatively rapidly moving the work-engaging member into initial contact with the work.

A still further object is to provide a device in which the work pistons may be held stationary and the body be made movable relative thereto.

From the following description of a presently preferred adaptation of the invention, it will be apparent that still further advantages are inherent in the invention and that it is susceptible of being carried out in physical structures varying from the specific form, arrangement and combination herein shown and described.

In the drawings, which will be referred to in conjunction with the following description:

Fig. 1 is a medial section;

Fig. 2 is an end view; and

Fig. 3 is a fragmentary enlarged section showing details of certain valve elements.

In the drawings, I show a body 1 presenting parallel cylinders 3, 4 and 5, valve-containing sockets 6, 7, 8 and 9, valve chambers 10, 11, passageways, 14, 15, 16, 17, 18, 19, 20, 21, 25, 26, 27, 28, 31 and 32, and a hydraulic fluid reservoir 30. The reservoir is at all times in communication with the inner ends 6a, 7a, 8a, 9a of the respective valve-containing sockets 6, 7, 8 and 9, and is also at all times in communication with the valve elements through passageways 25, 26, 27 and 28, respectively.

A pumping piston 35 is reciprocally mounted in cylinder 3 and has rods 35a, 35b projecting from opposite sides of the ends of the body through threaded plugs 36. Piston 35 divides cylinder 3 into chambers 3a, 3b. A first work piston 40 is reciprocally mounted in cylinder 4 and has rods 40a, 40b projecting from opposite ends of the body through plugs 41. Piston 40 divides cylinder 4 into chambers 4a, 4b. A second work piston 45 is reciprocally mounted in cylinder 5 and has rods

45a, 45b projecting through opposite ends of the body through plugs 46. Piston 45 divides cylinder 5 into chambers 5a, 5b.

Work-contacting members 50, 51 are disposed at the respective ends of the body 1, and are secured respectively to the opposite ends of the work piston rods 40a, 40b, 45a, 45b. Operating levers 52, 53, respectively, are pivotally mounted atop the respective members 50, 51. The levers are pivotally connected to the respective outer ends of the pumping piston rods 35a, 35b by means of links 55.

Valves 60, 61, 62 and 63 are mounted in the respective sockets 6, 7, 8 and 9. All said valves are of like construction and are more particularly described and claimed in my copending application Serial No. 508,444, filed October 30, 1943, but will now be described, like reference numerals applying to the component elements of each of the

20 said valves.

Each of the valves 60, 61, 62, 63 comprises a tubular body 70 held in its socket by snap ring 71. A poppet housing 73 is held in the inner end of the body 70 by a snap ring 74 and provides an inlet chamber 75 in communication with the reservoir through ports 76, 77, which latter port is controlled by poppet valve 77a seating towards the reservoir, being normally urged against its seat by a spring 78 and having oppositely disposed stems 79, 80. The outer end of each stem 78 is concaved as shown by dotted line in Fig. 3.

A tubular plunger 83 is reciprocally mounted in the outer end of the valve body, there being provided between its inner end and the inner end 35 wall of poppet housing 73 a pressure chamber 84, communicating with the inlet chamber 75 through a port 85 controlled by a ball valve 86 seating towards the inlet chamber. Pressure chamber 84 communicates with cylinder 4 through passageways 14, 15 and inlet chamber 75 communicates with cylinder 3 through passageway 18.

Plunger 83 has a longitudinal bore 83a in the left-hand or outer end of which a plug 88 is held by a snap ring 89, the plug having an opening 90. 45 The inner end of the plunger bore 83a has reciprocally mounted therein a secondary plunger 91 whose outer end is recessed at 92 to receive ball valve 86. A coil spring 87 is provided between the main plunger portion 83b and an annular flange on the secondary plunger. Port 81 in plunger 83 provides communication between the plunger bore and passageway 14.

A plug 94 fits in the inner end of a hollow poppet 93, being held therein by a snap ring 95 and having a port 97 therethrough. Poppet 93 is nor-

mally urged against its seat closing port 97 by a coil spring 89. Poppet 83 is normally urged against its seat closing opening 90 by a coil spring 100 and a discharge port 101 is provided through the outer end of poppet 83. A pull member 102 is provided on a plug 103 interposed between the snap ring 71 and the outer end of the body 70. A spring 105 interposed between the plug 103 and the annular flange 106 of plunger 83 normally urges said plunger inwardly to maintain ball 86 seated.

Within valve chambers 10, 11 the respective piston valves 114, 115 are reciprocally mounted for the purposes hereinafter to be described.

Poppet 77a of the valve element 60 is actuated by an eccentric cam 120 mounted on a shaft 121 journaled in the body and operated by an exterior handle 121a. The corresponding poppet 77a of valve element 62 is actuated by a like cam 125 mounted on a shaft 126 journaled in the body and operated by an exterior handle 127. The corresponding poppet 77a of valve element 61 is actuated by like cam 130 mounted on a shaft 131 journaled in the body and operated by an exterior handle which is not shown in Fig. 2 since it appears directly behind handle 121a in that view. And the corresponding poppet 77a of valve element 63 is actuated by a like cam 135 mounted on a shaft 136 journaled in the body and operated by an exterior handle which is not visible in Fig. 2 since it appears directly behind handle element 127.

Valve 114 is manually operable by a shaft 140 connected to the valve by a connecting rod 141, shaft 140 being journaled in the body and having an external operating handle 142. Valve 115 is manually operable by a shaft 145 connected to the valve by connecting rod 146, shaft 145 being journaled in the body and having an external operating handle 147.

The purposes and coaction of the elements which I have described will become apparent from the description of operation now to follow:

Assuming that member 50 is fixed and that body 1 is movable relative thereto, assuming valve 114 is to be moved to the right to the dotted line position 114a, assuming that valve element 61 is rendered inoperative by rotating cam 130 to unseat the poppet 77a and ball 86 of said valve element, and assuming further that valve element 63 is rendered inoperative by rotating cam 135 to unseat poppet 77a and ball 86 of that valve element, reciprocation of piston 35 by means of lever 52 will, on each inward stroke, draw fluid from the reservoir 30 into chamber 3a through passageway 18 by virtue of unseating poppet 77a of valve element 60. On each outward movement of piston 35—leftward movement in the drawings—this fluid will be trapped in chamber 3a and thus the body will be moved to the left by further outward movement of piston 35, since the spring pressure on ball 86 of valve 60 is sufficient to prevent that ball from being unseated by the fluid pressure in chamber 3a until the body 1 encounters a substantial resistance such as may be offered by the work load. Such resistance or work load would be positioned between the left-hand end of the body and the member 50.

During this initial movement of the body into contact with the work, make-up fluid is drawn into work chamber 4a from the reservoir through passageway 20, the vacuum unseating poppet 77a of valve element 62; and make-up fluid will be drawn into chamber 5a through passageway 31.

When the body 1 encounters the work load, further reciprocation of piston 35 will cause the fluid pressure to unseat ball 86 against its spring pressure on each leftward movement or pressure stroke of piston 35 and force fluid past ball 86, through passageways 14, 15 into chamber 4a to cause the body to exert the work moving or compressing pressure.

Inasmuch as the back pressure from chamber 10 4a will act against the relatively large area 83c of plunger 83, the pressure of spring 105 will be relieved against ball 86, the latter ball being urged towards its seat merely by the relatively weak spring 87, so that the relatively greater pressure of spring 105 does not have to be overcome on each pressure stroke of piston 35.

When the pressure in chamber 4a reaches a predetermined point, the fluid pressure acting upon ball 86 of valve element 62 will unseat that valve and pass into the relatively larger work chamber 5b and thus the work action will be carried on at a still more favorable volume-pressure ratio. The action of the pressure in chamber 5a against the plunger portion 83c of valve element 62 likewise compresses spring 105 of that valve until said pressure is relieved, so that the ball 86 of that valve is urged towards its seat merely by the relatively light action of spring 87.

From the foregoing it will be observed that the body is moved relatively rapidly into contact with the work load and then will automatically select the correct work piston (40 or 45) to overcome the load.

After body 1 has contacted the load, the pumping piston 35 may be made double-acting by moving valve 115 to the right to the dotted line position 115a, which will connect chamber 3b through the ports 19, 16, 15 with work chamber 4a, thus making pressure chambers out of both chambers 3a and 3b.

During the foregoing described operation of the device, the member 50 has been considered as fixed and body 1 has been considered as moving to the left. The body may be caused to move to the right by operating the cams 120, 125 to unseat the poppet 77a in valve elements 60, 62 to render those valve elements inoperative, and by rotating the cams 130, 135 to render valve elements 61, 63 operative and by moving valves 114, 115 to the left. With the valves in said relative positions, reciprocation of piston 35 will cause body 1 to move to the right in a succession of quick movements until a work load between the body and member 51 is encountered. Further operation will exert pressure on the load in the manner before described. Operation of the device in this position is substantially the same as before described except that in this case valve 61 is being used instead of valve 60.

My device may be operable also by making body 1 fixed and the members 50, 51 movable relative to the body, in which event, by the operation before described, member 50 would be moved towards and member 51 would move away from the body during the above-described operation of the device to move the body to the left towards member 50, and when operated to move the body to the right towards member 51, the members 50, 51 would be moved to the right.

If it be desired to lock the device hydraulically, this may be accomplished by leaving all the valves 60, 61, 62, 63, 114, 115 in the positions shown in the drawings.

Holes H are provided in the body 1 and in members 50, 51 so that it may be possible to sub-

ject any work to a tension load as by securing one side of the work to member 51 and one side to body 1, if the body is moving to the left, or by securing one side of the work to member 50 and one side to body 1, if the body is moving to the right. Or a compression load and a tension load may be simultaneously applied to the respective work loads, if desired.

I claim:

1. In a hydraulic pressure-generating device, the combination of a work-engaging body presenting a work cylinder, a pair of work-engaging members disposed respectively at opposite sides of the body, and hydraulic means for causing relative movement as between the body and the work-engaging members whereby to act upon work positioned therebetween, said means including a work position reciprocally disposed in the work cylinder, a pair of connecting rods projecting from opposite sides of the body, said rods being connected at one end to the work piston and connected at their other ends to the respective work-engaging members, a pressure-generating cylinder presented by the body parallel to the work cylinder, a pumping piston reciprocally mounted in the pressure-generating cylinder and forming therewith opposed pressure chambers to which the respective opposite faces of the pumping piston are exposed, ports providing communication between the pressure chambers and the work cylinder, valve means controlling said ports and being operable selectively to communicate pressure to the work cylinder at either side of the work piston therein, a check valve in each of said ports and a spring normally urging each of the check valves seated away from the work cylinder, each of said springs being yieldable only to a predetermined pressure whereby selectively to trap fluid in either of the pressure chambers until such predetermined pressure is generated therein.

2. In a hydraulic pressure-generating device, the combination of a body having oppositely disposed work-engaging sides, a transverse bore in the body providing a pressure generating cylinder, a pair of work-engaging members disposed in opposed relationship to the respective work-engaging sides of the body, a work cylinder in

the body parallel with the pressure generating cylinder, a pumping piston in the pressure generating cylinder, said piston having a rod extending outwardly through one of the work-engaging sides of the body, an actuating lever pivotally secured to one of the work-engaging members and operatively connected to the outer end of the rod, a work piston in the work cylinder, connecting rod means secured to opposite sides of the work piston and extending outwardly through the work-engaging sides of the body, said rod means being connected to the respective work-engaging members, a fluid reservoir, valve controlled means providing communication between the reservoir and pressure generating cylinder and valve-controlled means providing communication between the pressure generating and work cylinders.

3. In a hydraulic pressure-generating device, the combination of a body having oppositely disposed work-engaging sides, a transverse bore in the body providing a pressure generating cylinder, a pair of work-engaging members disposed in opposed relationship to the respective work-engaging sides of the body, a pair of work cylinders of relatively different diameters transversely of the body parallel to each other and to the pressure generating cylinder, a pumping piston mounted in the pressure generating cylinder, actuating means for said pumping piston, a work piston in each work cylinder, each work piston having opposite connecting rod means operatively connecting it to the respective work engaging members, a fluid reservoir, valve controlled means providing communication between the reservoir and pressure generating cylinder, valve controlled means providing selective communication between the pressure generating cylinder and the smallest work cylinder at opposite sides of the work piston therein, conduit means extending between the smallest work cylinder at opposite sides of the work piston therein respectively to the larger work cylinder at opposite sides of the work piston therein, a check valve in each of said conduits seating towards the smallest cylinder and spring means opposing movement of said valves off their respective seats.

HERBERT E. PAGE.
